US00D564093S

(12) **United States Design Patent** (10) Patent No.: **US D564,093 S**
Marchand et al. (45) Date of Patent: **** Mar. 11, 2008**

(54) **HANDLE FOR CATHETER DEVICE**

(75) Inventors: **Philippe Marchand**, Lake Forest, CA (US); **Yixin Hu**, Montreal (CA); **Ramin Sabbaghe-Kermani**, Laval (CA); **Michael Bailey**, Montreal (CA); **Michel Morelli**, Montreal (CA); **André Tremblay**, Laval (CA); **Teresa Mihalik**, Montreal (CA); **Daniel Patrick O'Sullivan, Jr.**, Mont Vernon, NH (US); **Stanley O. Thompson**, New Boston, NH (US); **Domenic Santoianni**, Kirkland (CA); **Vincent Nicolas Gladu**, Ville St.-Laurent (CA)

(73) Assignee: **CryoCath Technologies Inc.**, Quebec (CA)

(**) Term: **14 Years**

(21) Appl. No.: **29/259,385**

(22) Filed: **May 8, 2006**

(51) LOC (8) Cl. **24-02**

(52) U.S. Cl. **D24/133**

(58) Field of Classification Search D24/112, D24/113, 129, 130, 133, 138, 144, 216; 604/528, 604/523, 158, 164.13, 164.01, 95.01, 95.04; 600/585, 434

CLAIM

The ornamental design for a handle for a catheter device, as shown.

DESCRIPTION

FIG. 1 is rear perspective view of handle for a catheter device in accordance with the invention;

FIG. 2 is a right side view thereof;

FIG. 3 is a top view thereof;

FIG. 4 is a bottom view thereof;

FIG. 5 is a front perspective view thereof;

FIG. 6 is a front view thereof; and,

FIG. 7 is a rear view thereof.
